UNITED STATES PATENT OFFICE.

EMILIO A. MARAFFI, OF NEW YORK, N. Y., ASSIGNOR TO ELECTROLITE PRODUCTS CO., A COPARTNERSHIP, OF BROOKLYN, NEW YORK.

STAND.

Application filed May 4, 1925. Serial No. 27,922.

To all whom it may concern:

Be it known that I, EMILIO A. MARAFFI, a citizen of the United States of America, and resident of the city of New York, 5 Ozone Park, borough of Queens, in the county of Queens and State of New York, have invented a new and Improved Stand, of which the following is a full, clear, and exact description.

10 This invention relates to stands and has particular reference to a pedestaled receptacle which is especially designed for use as a smoking stand although the same, subject to minor changes, is capable of use 15 as a flower stand or other uses which fall within the scope of the invention.

One of the chief objects of the present invention is to provide a pedestaled receptacle which facilitates the removal and emptying of the refuse therefrom.

20 The invention furthermore comprehends a pedestaled receptacle or stand which includes a removable lower receptacle body and a vertically shiftable upper receptacle 25 body provided with a discharge opening in its lower end for discharging the refuse into the lower removable body, and in which the upper receptacle is gravitationally superimposed upon the lower receptacle body 30 normally whereby to clamp and maintain the said lower receptacle in seated relation on the pedestal.

As a further object the invention comprehends in a pedestaled receptacle which 35 is particularly designed for use as a smoking stand, having a match box holder arranged on the upper receptacle at one side thereof, a means of connection between the upper receptacle which permits of rotary 40 movement thereof on the pedestal so as to permit of the movement of the match box holder to a point within convenient reach without the necessity of turning the entire pedestal.

45 The invention furthermore comprehends a pedestaled receptacle or stand of the character set forth which is comparatively simple in its construction and mode of operation, inexpensive to manufacture, highly efficient in its purpose and attractive in its 50 appearance.

With the above recited and other objects in view, reference is had to the following specification and drawings in which there is

exhibited one example or embodiment of the 55 invention which is in no way intended as a limitation upon the scope of the appended claims as it is to be clearly understood that variations and modifications which properly fall within the scope of said claims may be 60 resorted to when found expedient.

In the drawings—

Figure 1 is a vertical sectional view through a stand constructed in accordance with the invention. 65

Fig. 2 is a plan view thereof.

Fig. 3 is a perspective view of the removable receptacle removed from the stand.

Referring to the drawings by characters of reference 10 designates a base having a vertical standard 11 being provided with a reduced upwardly projecting stem 12 providing at its juncture with the standard 11 a shoulder 13. The stem 12 is formed at its upper end with a substantially cup shaped head 14 constituting a seat for a removable receptacle body 15. An upper receptacle body 16 having a discharge opening 17 in its lower end is designed to seat or nest within the upper open end of the lower removable receptacle body 15 and the said upper receptacle body is formed with a depending marginal flange 18 which defines an annular channel 19 for engaging over the upper open end of the lower removable receptacle body. The upper receptacle body 16 is connected by diametrically disposed handles 20 with a weighted sleeve 21 slidably mounted on the stem 12 and limited in its sliding movement in an upward direction by the head 14 and in a lower direction by the shoulder 13. The lower end of the stem 12 is externally threaded at 22 and the upper end of the standard is provided with an internally threaded socket 23 whereby the stem is removably associated with the standard to permit of the ready assembly of the device 70 and at the same time to allow for disassociation of the parts for the purpose of storage and shipment. 85

In use of the device as a smoking stand, the upper receptacle 16 has mounted at diametrically opposite points thereon cigar or cigarette rests 24 and has secured to its upper edge a match box holder 25. The receptacle 16 functions in this instance as a hopper or tray into which the ashes, burnt 90

105

100

105

matches or other smoking refuse is thrown and from which the same is guided and discharged through the opening 17 into the removable lower receptacle body 15. When it is desired to empty the lower receptacle 15 the upper receptacle is shifted upwardly to the dotted line position thereby permitting of the removal of the lower receptacle 15 by means of its handle 26. When the lower receptacle 15 is replaced on the seat 14, the weighted sleeve 21 will serve to gravitationally effect the engagement of the channel 19 over the upper edge of the receptacle 15. In order to permit of the employment of the connecting handles 20 as a means for lifting and moving the stand, without effecting relative upward movement of the upper receptacle with relation to the pedestal, it is preferable to provide a latch 27 which is pivoted to the upper end of the standard 11 as at 28 and normally swung to a position to engage its nose 29 with an annular keeper bead 30 formed on the lower reduced end of the sleeve 21. The nose 29 and bead 30 are of a shape which permits the weighted sleeve to effect an automatic locking engagement of the latch with the bead so that said interlocking action is set up at all times. The latch is provided with an outwardly projecting manipulating handle 31 for the purpose of effecting the disengagement of its nose with the keeper bead when it is desired to remove the removable receptacle. It will be further noted that the construction admits of a rotary relative movement of the receptacle 16 so that the match box holder may be brought within convenient reach of persons on the opposite side of the stand without the necessity of turning the complete pedestal.

It is of course obvious that subject to minor changes the upper receptacle may be used as a plant holder, in which instance the drain water from the upper receptacle will be received in the lower receptacle, the removability of which lower receptacle admits of emptying of the drain water when necessary.

I claim:

1. A pedestal receptacle comprising superposed receptacles, the upper receptacle having an opening in its lower end, a standard upon the upper end of which, the lower receptacle seats and means slidably mounted on the standard and connected with the upper receptacle for supporting the same from the standard for vertical movement.

2. A pedestal receptacle comprising a pair of superimposed nested cup shaped receptacles the upper receptacle having an opening in its lower end for establishing communication between the receptacles, a standard having a seat at its upper end receiving the bottom of the lower receptacle and weighted means vertically slidable on

the standard and connected with the upper receptacle for gravitationally maintaining the receptacles in associated relation.

3. A pedestal receptacle comprising a pair of superimposed nested cup shaped receptacles the upper receptacle having an opening in its lower end for establishing communication between the receptacles, a standard having a seat at its upper end receiving the bottom of the lower receptacle, weighted means vertically slidable on the standard and connected with the upper receptacle for gravitationally maintaining the receptacles in associated relation and interengageable latch elements on the sleeve and standard for effecting a positive locking connection therebetween to prevent accidental upward movement of the sleeve with respect to the standard.

4. A pedestal receptacle comprising a pair of superimposed upper and lower nested cup shaped receptacles, the upper receptacle having an opening in its lower end for establishing communication between the receptacles, a standard having a seat in its upper end receiving the bottom of the lower receptacle and means vertically slidable on the standard and connected with the upper receptacle for normally effecting downward movement of the upper receptacle to maintain the same in associated relation with each other and with the standard.

5. A pedestal receptacle comprising a pair of superimposed upper and lower nested cup shaped receptacles, a depending rim on the upper receptacle embracing the upper open end of the lower receptacle when in nested relation, the said upper receptacle having an opening in its lower end for establishing communication between the receptacles, a standard having a seat in its upper end in which the bottom of the lower receptacle is seated, a weighted sleeve vertically slidably on the standard, handle members connecting the sleeve with the upper receptacle whereby the weighted sleeve constitutes means for normally moving the upper receptacle downward to clamp the lower receptacle between the upper receptacle and the seat on the standard.

6. A pedestal receptacle including a standard having a receptacle seat at its upper end, a lower removable receptacle having an open upper end and having its lower end seated in said seat, an upper receptacle having an opening in its lower end, superimposed upon and extending into the open upper end of the lower receptacle, and means vertically slidable on the standard and connected with the upper receptacle for effecting normal downward movement thereof to maintain the upper receptacle in superimposed engaged relation with the lower receptacle and the lower receptacle seated on the standard seat.

7. A pedestaled receptacle comprising a pair of superimposed nested cup shaped receptacles the upper receptacle having an opening in its lower end for establishing communication between the receptacles, a standard having a seat at its upper end receiving the bottom of the lower receptacle and weighted means vertically slidable on the standard and connected with the upper receptacle for gravitationally maintaining the receptacles in associated relation, the said standard having an enlarged lower section providing a shoulder for limiting the downward movement of the weighted means when the lower receptacle is removed.

8. A pedestaled receptacle comprising a pair of superimposed nested cup shaped receptacles the upper receptacle having an opening in its lower end for establishing communication between the receptacles, a standard having a seat at its upper end receiving the bottom of the lower receptacle and weighted means vertically slidable on the standard and connected with the upper receptacle for gravitationally maintaining the receptacles in associated relation, the said standard having an enlarged lower section providing a shoulder for limiting the downward movement of the weighted means when the lower receptacle is removed, the said standard sections being removably associated to permit of the assembly of the sleeve therewith and the disassociation of the elements of the device for shipment and storage.

9. A smoking stand comprising superimposed upper and lower nested cup shaped receptacles, the upper receptacle having an opening in its lower end and constituting a tray for receiving and discharging the smoking refuse into the lower receptacle, a match box holder secured to the upper receptacle at one side thereof, a standard having a seat in its upper end receiving the bottom of the lower receptacle, a weighted sleeve mounted for vertical sliding movement on the standard and connected with the upper receptacle for gravitationally maintaining the receptacles in associated relation, the connection between the upper receptacle and lower receptacle constituting handles for raising the upper receptacle to facilitate the removal of the lower receptacle for emptying the refuse and further

constituting means for rotating the upper receptacle to circumferentially shift the match box holder relative to the standard.

10. A smoking stand comprising superimposed upper and lower nested cup shaped receptacles, the upper receptacle having an opening in its lower end and constituting a tray for receiving and discharging the smoking refuse into the lower receptacle, a match box holder secured to the upper receptacle at one side thereof, a standard having a seat in its upper end receiving the bottom of the lower receptacle, a weighted sleeve mounted for vertical sliding movement on the standard and connected with the upper receptacle for gravitationally maintaining the receptacles in associated relation, the connection between the upper receptacle and lower receptacle constituting handles for raising the upper receptacle to facilitate the removal of the lower receptacle for emptying the refuse and further constituting means for rotating the upper receptacle to circumferentially shift the match box holder relative to the standard, the said sleeve and standard having interengageable latch elements for effecting a positive locking connection therebetween against relative upward movement of the sleeve with respect to the standard whereby the handles may be employed for lifting the complete device.

11. A pedestaled receptacle including a base having a seat at its upper end, a removable receptacle adapted to seat thereon, and means having vertical sliding connection with the base and respectively engageable with and disengageable from the upper end of the receptacle whereby to constitute means when in engaged position to hold the receptacle in place and when in disengaged position to permit of its removal.

12. A device of the character described, comprising a base having a seat at its upper end, a cup-shaped receptacle adapted to seat thereupon, a member adapted to engage the upper end of the cup-shaped receptacle to maintain the same in seated relation on the base, and means of connection between said member and the base to permit of relative movement of the member with respect to the base, whereby to effect the disengagement of the same from the receptacle to permit of its removal.

EMILIO A. MARAFFI.
